UNITED STATES PATENT OFFICE.

JOHN G. MUELLER, OF DAYTON, OHIO.

TRACK EQUIPMENT.

1,277,460.

Specification of Letters Patent.

Patented Sept. 3, 1918.

Application filed July 22, 1916. Serial No. 110,639.

To all whom it may concern:

Be it known that I, JOHN G. MUELLER, a citizen of the United States, residing at Dayton, in the county of Montgomery and State of Ohio, have invented certain new and useful Improvements in Track Equipment, of which the following is a specification, reference being had therein to the accompanying drawing.

10 My invention relates to track equipment.

One of the objects of the invention is to provide a rail brace to prevent the separating of the rails, the rocking of the rails, turning of the rails, side strain thereon and 15 split switches.

Another object is to eliminate the necessity for the present railroad tie by providing a combined brace and bed plate of the character herein described as a substitute therefor.

20 A further object is to provide a rail brace and tie which are simple in construction, durable in wear and easily assembled or disassembled by those unskilled in mechanics, 25 for use on either temporary or permanent tracks, detour tracks or main line railways, curves or switches.

Another object is to provide a rail brace and tie adjustable to varying gages of rail 30 way.

My invention can be either laid directly on the ground or embedded in a block of cement, wood, etc.

In the accompanying drawings, Figure 1 35 is a sectional elevation transversely of the rails showing the application of my invention thereto; Fig. 2 is a perspective view of my bed plate; Fig. 3 is a detail view showing the movable jaw adapted to coöperate 40 with the fixed jaws of the bed plate; Fig. 4 is a sectional elevation transversely of the rails showing a slightly modified form of my invention in which the bed plates are shown attached to blocks; Fig. 5 is a perspective 45 view of such bed plate; and Fig. 6 is a view illustrating a further modified form of the invention.

Referring to Figs. 1, 2 and 3 I have there 50 shown a pair of spaced apart bed plates 1 adapted to be located at each side of the track. Each of the bed plates is provided with a pair of fixed clamping jaws 2 located at the corners thereof. These jaws are provided with recesses 3 adapted to engage and 55 support the outer sides of the base flanges 4 of the rails 5. The inner portions of these

flanges are supported and engaged by means of coöoperating movable clamping members 6 provided with recesses 7 engaging such portions of the flanges 4. The clamping members or jaws 6 are slidably or adjustably mounted upon the bed plates 1 and for this purpose each bed plate is provided with an elongated central opening 8 having an enlarged portion 9 at one end and elongated 60 reduced edges 10 adjacent thereto. Each clamping member is provided with a downwardly extending tongue 11 provided with outwardly extending keys or lugs 12. The lugs 12 are of such size that they may be 65 inserted through the enlarged opening 9 of the bed plate while the tongue or projection 11 may be inserted through the elongated portion of the opening. A sliding movement inwardly of the clamping member will 70 cause the lugs to extend beneath the edges 10 whereby a bayonet locking engagement is assured which will prevent the removal of the clamping jaws 6. When the jaws are 75 in the position shown in Fig. 1 the lugs 12 80 will be in such position that they project beneath the edges 10, preventing the removal thereof.

Each pair of bed plates is connected by a suitable rail brace and for this purpose they 85 are provided with central lugs 13 having openings 14 and in a like manner each of the movable locking jaws 6 is provided with an opening 15 in alinement with the opening 14 of its plate. A brace rod 16 extends from one bed plate to the other transversely of the track with its ends projecting through the openings 14 and 15 of the bed plates. The ends of the rod are provided with suitable nuts 17 which retain it in position. A 90 spacer or tube 18 encircles the portion of the rod between the clamping members or jaws 6 and retains the latter in close clamping engagement with the rails. A nut 17 can be adjusted to insure better clamping effect. 95 When it is desired to vary the gage or the distance between the rails tubes similar to 18 may be inserted which are of various lengths and the nut 17 can again be adjusted 100 to draw the parts together.

In Figs. 4 and 5 I have shown a slightly modified form in which the bed plates 1 are provided with downwardly extending prongs or lugs 19 embedded in blocks 20 of cement, wood or any other suitable material. These prongs may be formed by casting the same upon the bed plates or by strik- 110

ing out portions of the bed plate itself. In other respects the general arrangement shown in Figs. 4 and 5 is the same as in Figs. 1, 2 and 3.

5 In Fig. 6 which illustrates a modified form of the clamping device the base plate is shown as comprising two sections 21 and 22 provided with coöperating clamping members or jaws 23 and 24. These jaws are 10 provided with transversely extending openings 25 and 26 adapted to receive a brace rod 27 which is removably and adjustably mounted within the openings and held in place by means of a nut 28. In order to 15 retain the clamping members or jaws for each rail in spaced apart relation I have provided a tubular spacer 29 of the character described above. The sections 21 and 22 are adjustable toward and away from each other 20 in order to cause the jaws 23 and 24 to properly engage the flange of the rail and for this purpose the adjacent edges are provided with screw-threaded recesses 30 and 31. Adapted to operate within these recesses is 25 a screw member 32 having its ends provided with right and left hand screw threads co-operating with the recesses 30 and 31. By rotating the member 32 the sections of the plate may be moved toward and away from 30 each other.

While I have shown and described one embodiment of the invention and several modifications thereof it will be understood that the same has been chosen for the purposes of illustration only, and that I do not desire to be limited to the details of construction shown and described, for obvious modifications will occur to a person skilled in the art.

40 Having thus fully described my invention, what I claim as new and desire to secure by Letters Patent, is:—

1. In a track equipment, a pair of bed plates each provided with fixed and movable clamping jaws, a brace rod connecting said plates and located between the plates and the rails, and means for clamping the jaws to the rails and holding the plates in spaced apart relation.

45 2. In a track equipment, a pair of bed plates each provided with a fixed jaw and a jaw interlocked therewith and slidably thereon, a brace rod connecting said plates, and means for clamping the jaws to the rails

and holding the plates in spaced apart relation.

3. In a track equipment, a pair of bed plates each provided with a fixed jaw and an adjustable jaw interlocked therewith, apertured portions upon the upper surface of the plates, apertured portions upon said adjustable jaw, a brace rod threaded through said apertured portions, and means for clamping the jaws to the rails and holding the plates in spaced relation apart.

4. In a bed plate, a pair of clamping jaws fixed to the upper side thereof, a central lug provided with an opening adapted to receive a brace, and a clamping jaw adjustably mounted upon said bed plate.

5. In a track equipment, a pair of bed plates each provided with a fixed clamping jaw and a portion provided with an aperture, an adjustable jaw coöperating with each fixed jaw and interlocked with the bed plate thereof, a brace rod threaded through said apertures, and means for retaining said bed plates in spaced apart relation.

6. In a track equipment, a pair of bed plates each provided with a fixed clamping portion, and a lug provided with an aperture upon the upper surface thereof, a slideable clamping jaw interlocked with each plate and provided with apertures in alignment with said first-mentioned apertures, a brace rod threaded through said apertures, and a sleeve interposed between said slideable clamping jaws and encircling said rod.

7. In a device of the character described, a bed plate provided with a fixed clamping jaw and a portion having an opening above the plane of the plate, an elongated slot in said plate, a movable jaw provided with an opening above the plane of the plate, a tongue projecting into said slot and interlocked with said plate, a brace rod passing through said openings, a sleeve surrounding a portion of said rod, and means at the end of said rod for forcing the movable jaw against said sleeve.

8. In a clamping device, a base provided with fixed clamping members at each side, a central apertured lug, and a second centrally located clamping member provided with an aperture in alignment with the aperture in said lug.

In testimony whereof I affix my signature.
JOHN G. MUELLER.
